US0D1110723S

(12) **United States Design Patent** (10) **Patent No.:** **US D1,110,723 S**
(45) **Date of Patent:** **** Feb. 3, 2026**

(54) **BRIEFCASE**

(71) Applicant: **Dell Products L.P.**, Round Rock, TX (US)

(72) Inventor: **Bruce A. Benzon**, Salt Lake City, UT (US)

(73) Assignee: **Dell Products L.P.**, Round Rock, TX (US)

(**) Term: **15 Years**

(21) Appl. No.: **29/923,274**

(22) Filed: **Dec. 28, 2023**

(51) LOC (15) Cl. **03-01**

(52) U.S. Cl.

USPC **D3/289**; D3/287; D3/283

(58) **Field of Classification Search**

USPC D3/289, 283, 287, 216

CPC A45C 3/02; A45C 11/002

See application file for complete search history.

CLAIM

The ornamental design for a briefcase as shown and described.

DESCRIPTION

FIG. 1 is a front perspective view of the briefcase comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof; and,

FIG. 7 is a bottom view thereof.

Broken lines shown in the drawings illustrate stitching presented as part of the claimed design.

1 Claim, 5 Drawing Sheets
